Primary Examiner — Mark A Goodwin*Assistant Examiner* — Benjamin M Weeks*(74) Attorney, Agent, or Firm* — Wood Herron & Evans LLP**(57) CLAIM**

An ornamental design for a garage door cam, as shown and described.

DESCRIPTION

FIG. 1 is a front left isometric view according to this invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines show portions of the garage door cam that form no part of the claimed design.
